UNITED STATES PATENT OFFICE.

ERNST MORITZ HALLBAUER, OF CHICAGO, ILLINOIS, ASSIGNOR TO AMERICAN CAN COMPANY, OF NEW YORK, N. Y., A CORPORATION OF NEW JERSEY.

SCREW-TOP FOR CANS.

No. 834,125.

Specification of Letters Patent.

Patented Oct. 23, 1906.

Application filed May 15, 1905. Serial No. 260,393.

To all whom it may concern:

Be it known that I, ERNST MORITZ HALLBAUER, a citizen of the United States, residing in Chicago, in the county of Cook and State of Illinois, have invented a new and useful Improvement in Screw-Tops for Cans, of which the following is a specification.

My invention relates to improvements in screw-top cans.

10 The object of my invention is to provide a screw-top can of a simple, efficient, strong, and durable construction, in which the screw-cap may be readily removed, however tightly it may become stuck or fixed by reason of the 15 sticky or gummy contents of the can, and this without danger of breakage.

My invention consists in the means I employ to practically accomplish this important object or result—that is to say, it consists in a 20 screw-top can having a screw-cap furnished with an upwardly-projecting rim and with a supplemental cap-disk having an upwardly-projecting deep flange or rim fitting inside the upwardly-projecting rim of the screw-cap, the two nesting rims of the screw-cap and supplemental cap-disk having a rolled, folded, or other seam uniting the same at their upper ends and reinforcing and stiffening the rims, said upwardly-projecting rims 25 of the screw-cap and supplemental disk being furnished with a diametrical slot to receive a nail or knife-blade or other implement to serve as a lever in unscrewing the cap.

My invention also consists in the novel 30 construction of parts and devices and in the novel combinations of parts and devices herein shown or described.

In the accompanying drawings, forming a 35 part of this specification, Figure 1 is a side elevation of a screw-top can embodying my invention. Fig. 2 is a plan view, and Fig. 3 is an enlarged central vertical section.

In the drawings, A represents a can or vessel of any suitable kind having a head a, furnished with flanges or collars a' a'' to receive the base b of the screw-top B, which is soldered thereto. The screw-cap B has screw-threads b' and an inturned flange b'' to serve as a seat for the cork disk or packing C 40 of the screw-cap D. The screw-cap D is furnished with screw-threads d and with upwardly-projecting extension or rim d' above the cork disk C.

F is a supplemental cap-disk having an upwardly-projecting deep flange or rim f fitting and nesting snugly within the upwardly-projecting rim d' of the cap-disk D. The upper ends of the nesting rims d'' and f are firmly and rigidly united together by a rolled seam f', which also serves to strengthen and stiffen the united nesting rims. The united and nesting rims d'' f are furnished with a slot D', preferably extending substantially diametrically of the screw-cap to receive any suitable tool or implement to act as a lever in unscrewing the cap. 55

G is a sheet-metal disk or washer interposed between the packing C and the supplemental cap-disk F to prevent said cap-disk sticking to the washer, and thus interfering 70 with the unscrewing of the cap. The supplemental cap-disk F has an annular shoulder or bead f'' to give it a narrow bearing on the disk or washer G, and thus enable the screw-cap to be more readily unscrewed. 75

By this means a very effective, tight, and perfect closure is produced, while at the same time the screw-cap may be readily loosened or unscrewed, however tightly it may be seated or stuck or fixed in place. 80

I claim—

1. In a screw-top can, the combination with a screw-top, of a screw-cap furnished with a cork or packing disk and having an upwardly-projecting rim extending above 85 the cork or packing disk, a supplemental cap-disk having an upwardly-projecting flange or rim fitting and nesting within said screw-cap rim, said nesting rims both being furnished with registering slots to receive a 90 lever for unscrewing the cap, and a sheet-metal disk or washer interposed between said cork or packing and said supplemental disk, said supplemental disk having a narrow annular projection bearing against said interposed washer, substantially as specified. 95

2. In a screw-top can, the combination with a screw-top, of a screw-cap furnished with a cork or packing disk and having an upwardly-projecting rim extending above 100 the cork or packing disk, a supplemental cap-disk having an upwardly-projecting flange or rim tightly fitting and nesting within said screw-cap rim, said nesting rims being both furnished with registering slots to receive a 105 lever for unscrewing the screw-cap, and said

nesting slotted rims having each an inward roll or fold at its upper end to strengthen and stiffen the same and cause them to mutually support each other, substantially as specified.

3. In a screw-cap can, the combination with a screw-top, of a screw-cap furnished with a cork or packing disk and having an upwardly-projecting rim extending above the cork or packing disk, a supplemental cap-disk having an upwardly-projecting flange or rim tightly fitting and nesting within said screw-cap rim, said nesting rims mutually supporting and bracing each and being both furnished with registering slots to receive a lever for unscrewing the screw-cap, and said nesting rims having a folded or rolled seam uniting the same at their upper ends and serving as an enlargement or reinforcement to strengthen and stiffen said nesting rims and cause them to mutually support each other when the lever is applied thereto to unscrew the cap, substantially as specified.

4. In a screw-cap can, the combination with a screw-top, of a screw-cap furnished with a cork or packing disk and having an upwardly-projecting rim extending above the cork or packing disk, a supplemental cap-disk having an upwardly-projecting flange or rim fitting and nesting within said screw-cap rim, said nesting rims being both furnished with registering slots to receive a lever for unscrewing the screw-cap, said nesting rims having a folded or rolled seam uniting the same at their upper ends and serving as an enlargement or reinforcing to strengthen and stiffen said nesting rims, and a sheet-metal disk or washer interposed between said cork or packing and said supplemental cap-disk, said supplemental disk having a narrow annular projection bearing against said interposed washer, substantially as specified.

ERNST MORITZ HALLBAUER.
